WRIST HELD THERAPEUTIC MAGNETIC DEVICE

Charles G. Popp, 1712 S. Clifton Ave., Park Ridge, Ill.
60068, and James R. Popp, 510 Roberts Drive, Glen-
wood, Ill. 60425

Filed Nov. 17, 1972, Ser. No. 307,489

Term of patent 14 years

Int. Cl. D24—04

U.S. Cl. D83—1 J

FIG.1

FIG.2

FIG.3

FIG.4

FIG. 1 is a top plan view embodying our novel design of a wrist held therapeutic magnetic device;

FIG. 2 is a side view thereof and the opposite side view would be identical;

FIG. 3 is a bottom plan view thereof; and

FIG. 4 is an end view thereof and the opposite end view would be identical.

We claim:

The ornamental design for a wrist held therapeutic magnetic device, substantially as shown.
